(57) **CLAIM**

The ornamental design for a sprocket tooth, as shown and described.

DESCRIPTION

FIG. 1 is a top left perspective view of a sprocket tooth illustrating my new design, the top right perspective view being a mirror image;

FIG. 2 is a front elevational view thereof, the rear elevational view being a mirror image;

FIG. 3 is a top planar view thereof, the bottom planar view being a mirror image;

FIG. 4 is an enlarged fragmentary top planar view thereof showing a portion of the sprocket tooth indicated by the dashed line circle 4 in FIG. 3; and,

FIG. 5 is an enlarged fragmentary front elevational view thereof showing a portion of the sprocket tooth indicated by the dashed line circle 5 in FIG. 2.

The broken lines shown in FIGS. 1-5 are included for the purpose of illustrating environmental structure and forms no part of the claimed design.
